UNITED STATES PATENT OFFICE.

CHESTER S. LEONARD, OF PHILADELPHIA, PENNSYLVANIA.

POLISHING-MACHINE.

SPECIFICATION forming part of Letters Patent No. 450,709, dated April 21, 1891.

Application filed November 13, 1890. Serial No. 371,309. (No model.)

To all whom it may concern:

Be it known that I, CHESTER S. LEONARD, a citizen of the United States, residing at Philadelphia, in the county of Philadelphia and State of Pennsylvania, have invented certain new and useful Improvements in Polishing-Machines; and I do hereby declare the following to be a full, clear, and exact description of the invention, such as will enable others skilled in the art to which it appertains to make and use the same.

The special object of the invention is to make a portable machine by which wood, metal, or stone may be conveniently polished, as hereinafter described.

Figure 1 of the drawings is a horizontal section of my portable polisher; Fig. 2, a longitudinal section on the dotted line $x-x$ of Fig. 1, and Fig. 3 a cross-section on the dotted line $y-y$ of Fig. 1.

In the drawings, A represents the frame of the machine, and $a-a$ bearings therein for the drive-shaft B, which is preferably made with a half-clutch b to connect with a like one on a flexible shaft. This shaft may, however, be driven by any suitable power mechanism without affecting the principle of my invention.

On the shaft B are made fast two worm-wheels $b'-b'$, which mesh into the corresponding worm-wheels $c'-c'$ on the vertical shafts C C. The latter turn in the bearings $a'-a'$ of frame A and are held by nuts $c-c$, while on

their lower ends are fastened the crank-arms c^2-c^2 , which turn in opposite directions. Each one of these crank-arms c^2 is attached at the end to a rod D by a pivot d . The rods D D are pivoted at one end to the arms c^2 and at the other to the slide-plates E E, so that these plates may reciprocate in opposite directions, carrying on the under side the polishing material F, secured in a recess thereof. The plates E are edge grooved at $e-e$ on the opposite sides, so as to slide longitudinally on the guide-tenons e' .

My machine may be readily transported and connected with any suitable power.

Having thus described all that is necessary to a full understanding of my invention, what I claim as new, and desire to protect by Letters Patent, is—

A portable polishing-machine consisting of the frame A, shaft B, carrying the fast worm-wheels $b'-b'$, the vertical shafts C C, carrying worm-wheels $c'-c'$ and crank-arms c^2-c^2 , the pivoted rods D D, and the oppositely-reciprocating plates E E to carry the polishing material, all substantially as shown and described.

In testimony whereof I affix my signature in presence of two witnesses.

CHESTER S. LEONARD.
